UNITED STATES PATENT OFFICE.

EARL J. CARD, OF JAMESTOWN, NEW YORK, ASSIGNOR TO ART METAL CONSTRUCTION COMPANY, OF JAMESTOWN, NEW YORK.

DESK.

Application filed August 18, 1921. Serial No. 493,208.

To all whom it may concern:

Be it known that I, EARL J. CARD, a citizen of the United States, residing at Jamestown, in the county of Chautauqua and 5 State of New York, have invented a new and useful Improvement in Desks, of which the following is a specification.

This invention relates to desks and particularly to metal pedestal desks of the 19 "knock-down" type, consisting of a plurality of parts which may be easily knocked down so as to effect a substantial saving of space in storage and shipment, and which may be readily reassembled for use. 15 The objects of the invention are to provide a simple and desirable desk of the type set forth, which may be easily and inexpensively manufactured of sheet metal; and also to provide a desk consisting of relatively 20 few parts and which while capable of being readily assembled and knocked down, will present in its assembled form a most rigid and sturdy structure. Further objects are to provide a knock-down desk having 25 improved connecting and reinforcing means; and to provide improvements in desks in the other respects hereinafter described and set forth in the claims.

In the accompanying drawings:

30 Fig. 1 is a front elevation of a desk constructed according to the invention.

Fig. 2 is a front elevation of the pedestal yoke or frame thereof.

Fig. 3 is a fragmentary perspective view 35 on an enlarged scale of a portion of said frame.

Fig. 4 is a fragmentary horizontal section of the desk on an enlarged scale on line 4-4, Fig. 6, showing the connection of said 40 frame with the pedestal.

Fig. 5 is a horizontal section of the desk on an enlarged scale.

Fig. 6 is a sectional elevation thereof on line 6-6, Fig. 1, on the same scale as Fig. 5.

45 Fig. 7 is a sectional elevation of a portion thereof on line 7-7, Fig. 6.

Fig. 8 is a sectional detail thereof on an enlarged scale showing the connection for the drawer locking frame.

50 Fig. 9 is a section thereof on line 9-9, Fig. 8.

Fig. 10 is a sectional elevation thereof on line 10-10, Fig. 1, on an enlarged scale.

55 Fig. 11 is a sectional elevation on line 6-6, Fig. 1, on an enlarged scale.

Fig. 12 is a sectional view on an enlarged scale showing the interlocking connection between the rear panels and the rear legs or corner posts.

Fig. 13 is an elevation of the locking 60 frame for the drawers.

As usual in pedestal desks, the desk comprises two end pedestals A separated by a knee space and one or both forming a support and housing for drawers B, or other 65 usual parts, and a top C covering the pedestals and intervening space. The rear ends of the pedestals are connected and held in proper relation as usual by a back wall or plate. In order to tie together the separated 70 front ends of the pedestals and their component walls and make the desk strong and rigid at its front, the pedestals are joined and braced by a yoke or connecting frame D which is preferably constructed 75 and detachably connected with the pedestals as presently explained, so as to enable the ready assembling and disconnection of the parts of the desks.

Referring to Fig. 2 of the drawings, the 80 preferred embodiment of the pedestal yoke D includes one or more U-shaped bars 15 which form the upright sides and bottom of the pedestal frame and which preferably terminate in horizontally bent ends 16. The 85 upright sides of each frame bar are connected by transverse drawer strike bars 17, and each strike bar 17 is preferably provided with a longitudinal rib 18 on its under side and is held in proper position and secured 90 to frame bars 15 by corner brackets 19. In the embodiment illustrated, the ribs 18 terminate short of the ends of the strike bars 17, and the brackets 19 form end continuations of ribs 18. These brackets are welded 95 or otherwise secured to the strike bars 17 and to the frame bars 15 and hold the strike bars rigidly and securely in place in the frame. A top frame bar 20 extends horizontally the length of the desk and is welded or otherwise secured to the bent ends 16 of the pedestal frame bars. This top frame bar maintains the upper ends of the pedestal frame bars in rigid and proper spaced 100 relation and forms the main connecting brace for the desk pedestals. Each of the pedestal frame bars 15 is preferably provided with a plurality of apertures 21, one pair between each pair of strike bars 17, to receive securing bolts or devices. 110

Each of the desk pedestals A is preferably formed by outer and inner side walls or plates provided with integral front and rear leg or post portions, said side walls being connected at their front ends by the pedestal frames 15 and at their rear ends by back panels hereinafter described. In the form illustrated, the side walls include side panels 22 formed with offset and substantially rectangular front legs 23 and rear legs 24 constructed by suitably shaping the plates which form the side walls. The front legs 23 are provided on their inner sides with vertically disposed grooves 25 which receive the U-shaped pedestal frame bars 15. The frame bars 15 are slipped vertically down into the grooves 25 and are secured therein, preferably by means of bolts 26 which extend through the apertures 21 in the frame bars and correspondingly positioned apertures in the grooved portions of the legs 23 and are fastened by thumb nuts. By securing the pedestal yoke in the grooves 25, a strong and rigid connection is formed by means of the readily removable thumb screws, and the frame bars of the pedestal yoke being flush with the inner faces of the legs are practically hidden from view. The front legs 23 preferably terminate at their inner edges in upright, inwardly extending flanges 27.

A bottom plate 28 (Fig. 7) which closes the bottom of each pedestal, is preferably formed, as shown, with downwardly bent, side flanges 30 which are received in grooves in the pedestal side panels formed by bending the lower edges of the side panels 22 inwardly and upwardly as at 31. The front edge of the bottom plate 28 is preferably bent downwardly and inwardly as at 32 to form a stiff front end for the bottom, and the rear edge of the bottom plate is bent downwardly as at 33 in the same manner as the side edges, being received in a groove formed by the inwardly and upwardly bent lower edge 34 of a back panel 35.

A plurality of drawer guides 36, preferably consisting of channel bars, are secured in proper spaced position in the desk with their front ends attached to the vertical flanges 27 of the legs and their rear ends attached to vertical supporting bars 37. As illustrated, these supporting bars are preferably of Z-shape in cross section, the inner flange of each bar having the drawer guides attached thereto and the outer flange being welded or otherwise secured to one of the pedestal side plates. The drawer guides are preferably secured in place by perforated ears 36^a thereon which are locked in slots in the flanges 27 and bars 37 by a rod 36^b extending through the perforations in the ears. The drawer guides are preferably further braced and held in proper position by one or more

spaced bars 38 to which the guides are similarly attached.

The webs of the bars 37 are each provided with a plurality of apertures 39 which receive tongues 40 formed on a rectangular drawer-locking frame 41. Drawer locking mechanism of any usual or suitable sort (not shown) is carried by the locking frame 41. This locking frame preferably has duplicate top and bottom transverse members 42 and 43 provided with oppositely bent flanges, the lower flange of the bottom member resting upon the bottom plate of the pedestal and the upper flange of the top member engaging and supporting the rear end of a horizontal plate 44 which supports a sliding shelf 45. The upright side members 46 of the locking frame 41 are preferably of angle form, the transversely extending front flanges of which carry the locking tongues 40. The locking frame is removably retained in place by interlocking its tongues in the slots of the supporting bars 38. Unintentional disengagement of the locking tongues from their slots is prevented by inserting small bolts or other suitable fastenings 46^a in registering holes in the frame 41 and the supporting bars 38. These bolts are only used for preventing the disengagement of the locking tongues, the latter being relied upon as the real securing means for the locking frame. Therefore, only a couple of the small bolts 46^a are required and the locking frame can be securely fastened in place very quickly.

The desk top C rests upon the upper edges of the pedestal side plates 22 and is preferably held in place by attaching strips 48 which are welded or otherwise secured to the top and depend therefrom between and in contact with the side plates, see Fig. 7. A similar strip 49 depends from the top in contact with the inner face of the back wall of the desk. These strips hold the upper ends of the upright walls 110 in place and cooperate with the pedestal yoke in making the desk rigid. The top C is preferably removably secured in place by screws 49^a driven through the outer pedestal walls 22 into the strips 48, 49. A depending ornamental edge flange on the top conceals the screws 49^a.

The back plates or panels 35 which form the rear walls of the pedestals are interlocked with the rear legs or corner posts on the pedestal side plates in such manner that a most rigid and strong joint is provided between the parts. In the form of connection illustrated, the ends of the back plates 35 are bent back upon themselves to form double thickness tongues 50, and then inwardly at substantially a right angle to form flanges 51. Complementary parts of the rear legs or posts are formed with grooves 52, preferably by bending an edge 125

of each leg inwardly, over, and outwardly to form the groove 52 and then angularly to form a flange 53 extending inwardly parallel to the flange 51 of the back plate 35. It is preferred to form these parts so that tongues 50 will fit snugly into the grooves 52 and hold the parts together. 54 designate small bolts connecting the flanges 51 and 53 for retaining the tongues in the 10 grooves and cooperating with the interfitting joints in securing these parts together.

The desk is preferably provided with one or more sliding shelves. In the embodiment illustrated, there are shown two such shelves 15 45, one in the upper part of each pedestal and arranged to slide beneath the desk top, and each shelf preferably comprises a plate provided with a pair of downwardly and inwardly turned side flanges 56 (Fig. 7).

20 57 designates rails on which the shelves slide and which are provided with downturned edges 58 under which portions of the side flanges 56 of the shelves extend and engage, to prevent displacement of the shelves. The 25 front edge of each shelf preferably terminates in a downwardly and inwardly bent ornamental flange 59 which also provides a hand grip for facilitating withdrawal of the shelf.

30 The top plate C and the shelves 45 are preferably covered with the usual mat or pad of linoleum or other suitable covering material, held in place by means of marginal strips 60 of metal, which embrace the downturned edge flanges of the top plate and of the shelves.

The desk is preferably provided with a centrally positioned drawer 62 between the two pedestals. As best illustrated in Figs. 40 7 and 10, this drawer 62 may be mounted in any usual manner to slide on drawer guides or channels 63 suitably supported on the inner pedestal walls 22 beneath the top of the desk. 64 designates a housing plate for the central drawer enclosure, suitably secured to the inner pair of pedestal side walls by bolts or the like as at 65. This housing plate has a vertical back 66, the ends of which are secured by attaching strips 67 to the inner pedestal walls, see Figs. 5 and 10.

I claim as my invention:

1. In a metal desk, the combination of 55 separated upright pedestals, a desk top bridging said pedestals, a pedestal connecting and bracing yoke comprising a top bar which extends from one pedestal to the other beneath said desk top and upright bars rigidly connected to and extending downwardly from said top bar beside said pedestals, and means for securing said upright bars to said pedestals.

2. In a metal desk, the combination of 60 separated pedestals each comprising inner and outer upright side members, a desk top bridging said pedestals, a pedestal connect-

ing and bracing yoke comprising a top bar which extends from one pedestal to the other beneath said desk top, and upright frames rigidly secured to and extending downwardly from said top bar, one frame 70 between the side members of each pedestal, and means for securing said frames to said pedestal side members.

3. In a metal desk, the combination of 75 separated upright pedestals having upright grooves in their sides, a desk top bridging said pedestals, a pedestal connecting and bracing yoke comprising a top bar which extends from one pedestal to the other beneath said desk top and upright bars rigidly 80 connected to and extending downwardly from said top bar in said grooves, and means for removably securing said upright bars in said grooves.

4. In a metal desk, the combination of 85 separated pedestals, each comprising inner and outer upright side members provided near their front ends with facing upright grooves, a desk top removably secured on said pedestals, a pedestal connecting and 90 bracing yoke comprising a top bar which extends from one pedestal to the other beneath said desk top, and upright frames rigidly secured to and extending downwardly from said top bar, one frame 95 between the side members of each pedestal and seated in said grooves, and means for removably securing said frames to said pedestal side members.

5. In a metal desk, the combination of 100 pedestal side members having front leg forming portions with upright grooves in their inner sides, a front pedestal frame having side bars located in said grooves, and means for securing said pedestal frame 105 and said front legs together with said side bars in said grooves.

6. In a metal desk, the combination of a 110 pedestal frame having upright spaced side bars, drawer strike bars connecting said side bars, desk legs having upright grooves in their inner sides for receiving said side bars, and means for securing said pedestal frame and said legs together with said side bars in said grooves.

7. In a metal desk, the combination of a 115 pedestal frame having upright spaced side bars, drawer strike bars connecting said side bars, pedestal side plates having hollow leg forming portions provided with upright grooves in their inner sides for receiving said side bars, and means for securing said pedestal frame and said side plates together with said side bars in said grooves.

8. In a metal desk, the combination of a 120 pedestal comprising a front frame having a pair of spaced side bars and strike bars connecting said side bars, side and back plates connected together and enclosing a drawer space, means connecting said frame 125

130

- with said connected plates, drawer guides in said pedestal, and means connecting said drawer guides to the sides of said pedestal.
9. In a metal desk, the combination of side supporting members, means detachably connecting said side members at the front of the desk, a back member connecting said side members at the rear of the desk, said back member having tongues at its opposite vertical edges and lateral flanges spaced inwardly from said edges, and disposed opposite to and spaced from said side members, said side members having in their inner sides vertical grooves into which said tongues extend in the direction of the plane of the back member, and releasable fastenings connecting said flanges and side members and acting when tightened to draw said flanges and side members toward each other to force said tongues firmly into said grooves and rigidly but detachably connect said side and back members.
10. In a metal desk, the combination of side supporting members, means connecting said side members at their front ends, and a back plate connecting said side members, the opposite side edges of said back plate being bent upon themselves and then laterally to provide edge portions of double thickness and forwardly projecting flanges, said side members having vertical grooves in their inner sides adapted to receive said doubled edge portions of the back plate and also having flanges opposite to and spaced from said flanges of said back plate, and detachable fastenings connecting said opposite flanges and acting when tightened to draw said flanges towards each other to firmly seat said edge portions in said grooves and rigidly but detachably connect said back plate and side members.
11. In a metal desk, the combination of separable metal wall members, one of which members is bent to form a projecting tongue and a flange extending at an angle from said tongue, said other member being bent to form a groove adapted to receive said tongue and a flange disposed opposite to and spaced from said first mentioned flange, and detachable fastenings connecting said opposite flanges and acting when tightened to draw said flanges towards each other to force said tongue firmly into said groove and rigidly but detachably connect said wall members.
12. In combination in a metal desk, a drawer pedestal, comprising a pair of spaced vertical side members, a separable unitary frame which is formed with upright side bars and horizontal drawer strikes and detachably connects said side members at their front ends, drawer guides connected at their front ends to said side members, a pair of spaced vertical bars secured to said side members and connected to and supporting the rear ends of said drawer guides within said pedestal, and a separable unitary transverse drawer locking frame having a releasable interlocking connection with said vertical bars and tying together the side members at their rear portions.
13. In combination, in a metal desk, a drawer pedestal comprising a pair of spaced vertical side members, a separable unitary rigid upright frame which has upright side bars and transverse drawer strikes and detachably connects said side members at their front ends, drawer guides removably secured within said pedestal, and a separable unitary transverse drawer locking frame detachably secured to said side members and rigidly connecting said members at their rear portions, said drawer locking frame forming a removable support for a drawer locking mechanism.
14. In combination in a metal desk, a drawer pedestal comprising a pair of spaced vertical side members, a frame detachably connecting said side members at their front ends, a plurality of drawer guides connected at their front ends to said side members, a separable drawer locking frame arranged transversely within said pedestal, and including a pair of upright side bars having tongues thereon, and a pair of spaced vertical bars secured to said side members and to which the rear ends of said drawer guides are attached, said vertical bars having apertures therethrough to receive the tongues of said locking frame.
15. In a metal desk, the combination of pedestal side members having front leg forming portions with upright grooves in their inner sides, a front pedestal frame comprising a top bar and upright bars rigidly connected to and extending downwardly from said top bar in said grooves, and means for releasably securing said upright bars in said grooves.

EARL J. CARD.
